UNITED STATES PATENT OFFICE.

WILLIAM M. MITCHELL, OF LOUISVILLE, KENTUCKY.

RAIL-ANCHOR.

1,262,827.

Specification of Letters Patent. Patented Apr. 16, 1918.

Application filed February 10, 1917. Serial No. 147,762.

To all whom it may concern:

Be it known that I, WILLIAM M. MITCHELL, residing at Louisville, State of Kentucky, have invented certain new and useful 5 Improvements in Rail-Anchors, of which I do declare the following to be a full, clear, and exact description, reference being had to the accompanying drawings, forming a part of this specification.

10 The present invention has for its object to provide an improved construction of rail anchor designed to prevent the longitudinal creeping of the rails of railway tracks, an example of this type of rail anchor being 15 set forth in Letters Patent No. 1,184,478, granted to me May 23, 1916.

The invention consists in certain features of improvement tending to simplify and cheapen the construction of the rail anchor 20 and increase its efficiency and these features of improvement are set forth in the following specification, illustrated in the accompanying drawings and particularly pointed out in the claims at the end of this specification.

25 Figure 1 is a plan view showing my improved rail anchor in position upon a rail, a portion of one of the ties of a railway track being also shown. Fig. 2 is a view in cross section on line 2—2 of Fig. 1. Fig. 3 is a view in cross section on line 3—3 of Fig. 1. Fig. 4 is a view in end elevation. Fig. 5 is a view in horizontal section on line 5—5 of Fig. 2. Fig. 6 is a view similar to Fig. 5 but 30 showing the parts in different positions.

35 A designates a railway rail, the base flanges α and α' of which will be engaged by the rail anchor and B denotes one of the railway track ties that will be engaged by 40 the abutment or foot of the rail anchor when the anchor is in operative position upon the rail.

45 My improved anchor comprises a body member C and a movable jaw member D that is adapted to interlock with the body member as will hereinafter more fully appear. In the preferred form of my invention, illustrated in the accompanying drawings, the body member C is formed as a 50 casting being provided at one end with a rigid jaw C' preferably formed integral with the body member C. This rigid jaw C' has a groove to receive one of the base flanges α of the rail A, the upper inwardly 55 extending portion of the rigid jaw C' being adapted to engage the upper surface of the

base flange α of the rail. The outer wall of the groove in the rigid jaw C' is formed with the inwardly extending portion c' and with the inclined faces c^2 and c^3 extending outwardly from this central portion c' , as clearly shown in Fig. 5 of the drawing. The purpose of thus constructing the outer wall of the groove of the rigid jaw C' will hereinafter more fully appear. 60 65

At its opposite end the body member C of my improved rail anchor is formed with a suitable abutment or foot C² adapted to bear against the vertical face of the adjacent track tie B and upon the upper face of 70 this end portion of the body member is formed the rib c^4 that will be engaged by the movable jaw or member D. Outside the rib c^4 the upper face of the body member C is shown as formed with serrations or teeth 75

c^5 adapted to engage with serrations or teeth d formed on the underside of the outer portion of the movable jaw or member D. Instead of forming the vertical rib c^4 as a T-shaped rib (that is to say a rib having 80 portions projecting laterally in both directions from its upper part) I form this rib with one of its vertical walls flat, this flat wall being preferably the outer wall c^6 . The upper portion of the rib c^4 is formed upon 85

its inner side with a head or projecting portion c^7 adapted to interlock with a projecting rib d^2 that is formed at the lower portion of the inner depending wall d^3 of the movable jaw or member D. It will thus be 90 seen that the cavity of the movable jaw member D that receives the rib c^4 will be of a shape corresponding to that of the rib and by forming the rib c^4 and the cavity of the movable jaw D that receives this rib, of the 95 shape shown, a material saving in metal and cost of manufacture is effected since no coring of the pattern is necessary in forming the flat outer face of the rib c^4 , such as would be required if the outer face of the 100 rib were formed at its top with a laterally extending head or portion.

At the base of the rib c^4 there is formed a vertical stop or shoulder c^8 that has two functions, first, to prevent any attempt to place the movable jaw member upon the rib except by slipping this jaw member over the opposite end of the rib, and second, to provide a bearing at the end of the rib c^4 for the edge of the base flange α' of the rail A. 105

At the opposite end of the inner face of the rib c^4 there is formed a stop or shoulder 110

c^9 adapted to engage the outer edge of the base flange a' of the rail when the anchor is in such interlocking engagement with the rail as to prevent the creeping of the rail in the direction of the arrow, Fig. 6.

5 In applying my improved rail anchor to a rail, the body member C will first be slipped under the base of the rail and the rigid jaw C' will be engaged with the base flange a of the rail, after which the opposite end of the body member C will be raised until the upper face of the body member bears against the bottom of the rail and the edge of the flange a' engages the 10 stops c^8 and c^9 at the opposite ends of the raised rib c^4 . The movable jaw or member D will then be slipped over the end of the rib c^4 farthest from the abutment C^2 and this movable jaw member will be forced 15 toward the abutment until the inclined bearing surface at the bottom of its inner depending portion d^4 bears against the upper inclined surface of the base flange a' of the rail. When the anchor is thus in position 20 for use, the initial creeping of the rail A in the direction of the arrow Fig. 5 will cause a slight rocking of the anchor thereby causing it to turn from the position shown in Fig. 5 to the position shown by full and dotted lines in Fig. 6, at 25 which time the flanges a and a' of the rail will be gripped between the inclined face c^2 of the rigid jaw C' and the shoulder c^9 at the opposite end of the body member C.

30 Inasmuch as there is often a tendency of the rail anchor, particularly when it becomes embedded in the ballast of the track, to be shifted away from the tie B particularly by the action of the frost in the ballast, it is desirable to so form the anchor that when such 35 shift occurs there shall still be a clamping of the anchor at its opposite ends against the flanges of the rail, and with my improved anchor it will be seen that if the body member C of the anchor is moved outwardly 40 from the tie B under such conditions, the oppositely inclined outer wall of the groove in the rigid jaw or member C' will permit this slight shift to occur and at such time 45 the rail will then be gripped between the inclined face c^2 of the rigid jaw C' and the stop shoulder c^8 at the end of the rib c^4 nearest the abutment c^2 . While I prefer to form the outer wall of the groove in the 50 rigid jaw C' with flat faces oppositely inclining from the central point of the wall, it is obvious that this wall of the groove 55 might be made upon a curve.

By forming the rib c^4 with a flat face and 60 by forming the groove in the movable jaw D with a corresponding flat face, not only is a material saving of metal effected, but the cost of manufacture is considerably lessened. So, also, by providing the stops or 65 shoulder c^8 and c^9 at the ends of the rib c^4 ,

a more effective gripping of the flange a' of the rail is insured than would be the case if a shoulder to engage the flange extended continuously from end to end of the rib c^4 , and a saving of material is also effected. 70 The feature of employing a stop c^8 of such construction as to prevent any improper application of the movable jaw to the rib c^4 is also important, as it insures that even in the hands of careless workmen the movable 75 jaw D will be properly interlocked with the rib c^4 of the body member.

It will be understood that the precise details above set forth may be varied without departing from the spirit of the invention 80 and that features of the invention may be employed without its adoption as in entirety.

Having thus described my invention, what I claim as new and desire to secure by Letters Patent is—

1. A rail anchor comprising a body member provided at one end with a jaw to engage one of the base flanges of the rail and provided at its other end with a movable jaw 90 to engage the opposite base flange of the rail, means for connecting said movable jaw to said body member comprising an interlocking rib and groove flat on one side and offset on the other side, said rib and groove being located above the top of the body portion of the anchor.

2. A rail anchor comprising a body member provided at one end with a jaw to engage one of the base flanges of the rail and provided at its other end with a movable jaw 100 to engage the opposite base flange of the rail, said movable jaw being formed with a downwardly open groove having a flat wall on one side and an offset wall on the opposite side, the body member being provided with a vertical rib having one side flat and having the opposite side offset at its top to enter the groove of said movable jaw.

3. A rail anchor comprising a body member provided at one end with a jaw to engage one of the base flanges of the rail and provided at its other end with a movable jaw to engage the opposite base flange of the rail, means for connecting said movable 115 jaw to said body member comprising an interlocking rib and groove, and a stop projecting from one end of said rib to prevent the improper engagement of the movable jaw with the body member.

4. A rail anchor comprising a body member provided at one end with a jaw to engage one of the base flanges of the rail and provided at its other end with a movable jaw to engage the opposite base flange of the 125 rail, and means for connecting said movable jaw to said body member comprising a rib rising vertically from said body member and provided at its opposite ends with stops to engage the edge of the base flange of the 130

rail, said movable jaw being provided with a groove to receive said rib.

5. A rail anchor comprising a body member provided at one end with a jaw to engage one of the base flanges of the rail and provided at its other end with a depending abutment to engage a tie and with a movable jaw to engage the opposite base flange of the rail, said body member being provided also above said abutment with a vertical rib and with stops at the ends of said rib, the stop nearest the abutment being arranged to prevent the improper engagement of the movable jaw with the body member 15 and said movable jaw being provided with a groove to receive said rib.

6. A rail anchor comprising a body member provided at its opposite ends with jaws to engage the base flanges of the rail, one of 20 said jaws having the inner vertical face of

its wall disposed at an angle outwardly in each direction from its center, the opposite jaw being provided at its ends with inwardly extending lugs to engage the adjacent base flanges of the rail.

7. A rail anchor comprising a body member provided at one end with a jaw to engage one of the base flanges of the rail and provided at its other end with an abutment to engage a tie and provided also with a jaw above said abutment to engage one of the base flanges of the rail, said body member being provided at the end adjacent said abutment with a plurality of stops to engage the adjacent edge of the rail flange and having a jaw at its opposite end formed with a vertical wall inclined outwardly in both directions.

WILLIAM M. MITCHELL.
